PAUL J. HENTSCHEL, OF BALTIMORE, MARYLAND, ASSIGNOR TO MONARCH PRODUCTS COMPANY, OF BALTIMORE, MARYLAND, A CORPORATION OF MARYLAND

GREASE ABSORBING AND DEFLECTING ATTACHMENT FOR GAS-STOVE FLUES

Application filed May 18, 1929. Serial No. 364,192.

My said invention relates to an improved combined grease absorbent device and deflector designed for attachment to the oven flue outlets of gas ranges.

5 The invention aims to provide a simple economical and efficient device which may be readily attached to the flue ring and which will effectively collect the sooty and greasy particles contained in the gases issuing from the flue, and which will deflect the purified gases forwardly away from the wall adjacent which the gas range is usually located.

10 With these and other objects in view, the invention includes the novel features of construction and arrangement and combination of parts hereinafter described and defined by the appended claims.

What I at present consider preferred embodiments of the invention are illustrated in the accompanying drawings in which:

Figure 1 is a section on line 1—1 of Fig. 2 showing my device as applied to the flue ring of a gas stove oven, the top wall of 25 which is shown in part in a conventional manner.

Fig. 2 is a front elevation of the device partly broken away and with the flue ring shown in section.

30 Fig. 3 is an inside face view of the frame member.

Fig. 4 is a similar view showing the cover, pad, and retaining springs in place, with parts broken away.

35 Fig. 5 is a detail view of the supporting standard and clamp in partial rear elevation.

Fig. 6 is a transverse sectional detail through one of the side bars or walls.

Fig. 7 shows in front view and side elevation a modified form of supporting bracket.

Fig. 8 is a section on line 8—8 of Fig. 9 showing a modification.

Fig. 9 is a front elevation of the same.

45 Fig. 10 is a fragmentary section on line 10—10 of Fig. 9.

Fig. 11 is an inside face view of the frame and

50 Fig. 12 is a view of the cover member partly broken away.

In this drawing, 1 designates the top of a gas range (shown in part conventionally) having the outlet opening 1^a encircled by the customary flue ring or flange 2.

3 designates a frame of generally rectangular form which may be conveniently and economically made of cast iron, the side walls 3^a of which are curved so as to approximate a quarter circle.

This frame is intended to have its lower 60 cross bar or member 3^b secured to the back edge of the flue ring in the manner herein-after described, so that the side arms will extend upwardly and forwardly with relation to the flue ring.

65 The side bars 3^a and lower and upper cross bars 3^b and 3^c are provided with inwardly extended flanges a, b, and c, respectively, and are further provided with lugs a', b', and c' respectively, the purpose of 70 which will hereinafter appear.

4 designates a pressed sheet metal cover member which is provided with offset edges 4^a at its lower and upper ends designed to underlie the flanges b and c respectively, and with correspondingly offset side edges 4^b (Fig. 2) designed to underlie the side flanges a, this flange formation making the inner or concave face of the cover in the form of a curved tray so to speak, within which is 80 placed a pad of absorbent material such for example as a sheet of asbestos indicated at 5

The dimensions of the cover 4 are such that its upper edge may be inserted and slid past the lugs a' and into engagement with the spaces between flange c and lugs c', after which the lower edge may be swung past lugs b' and into engagement with flange b, the side edges engaging the under sides of flanges a.

For holding the cover and its absorbent pad in place in the frame I provide a plurality of leaf springs 6, preferably formed flat and having their ends seated in the recesses, or grooves formed by the lugs b' and c', so that the thus bowed springs bear against the 90 inner face of the pad 5 at the center and side margins.

7 designates what I term a ventilator which consists of a pressed sheet metal plate having elongated openings forming horizontally 100

disposed louvers for the passage of combustion gases and cooking vapors, such openings being preferably formed by slitting the metal and pressing the slitted portions downwardly or inwardly as indicated at 7^a forming gas collectors which deflect the gases into the space behind the ventilator. This ventilator has its lower edge supported by the lugs b', while its upper portion is supported in spaced relation to the pad 5 by the lugs a'.

My preferred means for supporting the deflector in position relative to the ring or vent collar 2 comprises the following instrumentalities.

8 designates a steel bracket post which has an offset lower end portion 8^a. A short plate member 8^b is spot welded or otherwise suitably secured to the bracket 8 and extends down opposite the offset portion 8^a so as to form a groove or channel to receive the flue ring 2 to which it is clamped by set screw 9.

Preferably the lower part of the plate or member 8^b is folded back upon itself as indicated at 8^c and the hole for the screw is thus tapped through a double thickness of metal which affords ample thickness for screw threads.

9' designates a deflector frame carrying member or slider which has a vertical passage 9^a designed to slidably engage the bracket or bar member 8 and be held locked thereon at any desired elevation by thumb screw 10 threaded through the back wall.

35 The member 9' has a lug or flange projecting from its forward face which flange has its upper face inclined to correspond to the angle of inclination of the lower cross bar 3^b which latter is secured to the flange 9^b by means such as rivets passing through alining openings in the parts.

From the above description, it will be seen that I provide a very simple construction capable of being economically manufactured and readily assembled and applied to the flue ring. When in place, the ascending grease and soot laden particles will be caught by the downwardly flaring vanes of the ventilator member and deflected upward against the absorbent pad which will collect and retain the grease and soot particles, and the purified gases will be deflected forwardly and downwardly beneath the lower edge of cross member 3^c.

55 Due to the fact that the deflector is open at the sides and the space between it and the flue outlet is in unobstructed communication with the outside air the upward flow of the flue products tends to draw in therewith a portion of the air which mingles with the flue products and passes therewith through the openings in the ventilator sheet. This air, which is of course, much cooler than the products of combustion, has a cooling or chilling effect on the greasy products contained in

flue gases and facilitates the deposit thereof on the asbestos sheet on contact therewith.

Due to the fact that the pad is retained solely by the springs which are detachably held by the lugs, it is a simple matter to remove the pad and replace it with a fresh one when this is desirable.

While it is desirable for some stoves to provide a connection with the flue ring which will enable the collector to be adjusted vertically, this may not be necessary in other cases, in which event, I may provide the form of supporting bracket indicated at 11 in Fig. 7 having an inclined upper face portion 11^a adapted to be riveted to the cross bar 3^b and a so bifurcated lower part 11^b adapted to be clamped to the flue ring.

In the modification shown in Figs. 9 to 12 inclusive, I make the attaching means as an integral part of the frame by casting the frame and bracket in one piece, such integral bracket being indicated at 11*.

In this form, I dispense with the use of holding springs for the pad or grease collecting layer and likewise the use of lugs to hold the ventilator.

To this end, the frame is provided with holes 12 at its corners to receive screws 13 which engage threaded openings in projections or hollow studs 14 carried at the corners of the ventilator.

The cover member 4* is made of less length than the distance between the holes and the absorbent or collecting sheet 5* which is pressed or molded to curved form to conform to the inner face of the cover plate, projects beyond the upper and lower edges of the cover member and is provided with correspondingly alined holes. In assembling, the cover plate 4* and sheet 5* are applied to the frame and then the ventilator is placed in position with the hollow studs 14 bearing against the sheet 5* with their bores alined with the holes, and the screws are inserted and screwed into the threaded bores of the studs to clamp the part together. In this form, the ventilator is arranged concentric to the cover plate so that it is spaced therefrom as widely at the bottom as at the top.

To replace the pad, it is only necessary to remove the screws, separate the parts, and reassemble with a fresh pad.

Having thus described my invention, what I claim is:

1. A device for catching flue impurities comprising a frame composed of cross bars and connecting carrying side bars having inwardly extended flanges, a closure member having flanged edges engaging said aforesaid flanges, an absorbent sheet carried by the inner face of said closure member, means for holding such sheet in position, and means for securing said frame to a flue ring.

2. A device for catching flue impurities comprising a main curved member, means for

- connecting one edge to a flue ring, an impurity intercepting sheet carried by said member on its concave side and a curved ventilator sheet beneath said intercepting sheet and spaced therefrom, said ventilator sheet being arranged substantially concentric to said main member, and having elongated horizontally disposed gas deflecting passages.
3. A device for catching flue impurities comprising a curved frame having means for attachment to a flue ring, a curved cover member, a curved sheet of grease collecting material within said cover member, a ventilator curved to conform to said frame, cover member and sheet, and means for securing said parts together with the ventilator spaced from the collecting sheet and concentric therewith.
4. A device according to claim 3 in which the attaching means comprises hollow studs at the corners of the ventilator having threaded bores and screws passing through openings in the frame and collecting sheet and engaging said bores.
5. A device for catching flue impurities of gas stoves comprising a carrying member in the shape of an open frame, means for supporting said frame from the flue ring so as to project upwardly and forwardly over the flue outlet, a sheet metal closure member carried by said frame, an impurity intercepting sheet overlying the inner face of said closure member and a ventilator beneath said interceptor sheet and spaced therefrom, said ventilator comprising a sheet of metal having horizontal slits with the portions of the sheet above said slits deflected inwardly.
6. A deflector and gas separator for the outlet flues of gas stoves comprising a main carrying member of substantially the shape of a quarter segment of a cylinder having means at its lower edge for connecting it to the back wall of the flue ring of the gas stove, an impurity intercepting sheet overlying the inner face of said main member, and a ventilator member overlying the inner face of said interceptor sheet and spaced therefrom, said ventilator member comprising a metal sheet curved to conform to the main carrying member and having horizontal slits at intervals from its top to its bottom edges with portions of the sheet adjacent said slits deflected inwardly whereby portions of the flue gases are separated and deflected by said deflected portions into contact with the interceptor sheet.
7. The combination with the flue outlet of a gas stove, of a carrying member rigidly supported adjacent said outlet and extending upwardly and forwardly over said flue outlet, said member having relatively narrow side edges, the space between said member and said outlet being substantially free and unobstructed at the front and both sides, and an incombustible impurity intercepting sheet located on the under side of said member.
8. The combination with the flue outlet of a gas stove, of a curved carrying member conforming approximately in shape to a quarter of a cylinder, said member having relatively narrow side edges, means securing one edge of said member adjacent the back of said flue outlet in such position that said member curves upwardly and forwardly over said flue outlet leaving the space between said member and outlet freely open and substantially unobstructed at the front and sides, and a curved incombustible grease interceptor sheet located on the under side of said curved member.
9. The combination with the flue outlet of a gas stove, of a member supported adjacent to and extending upwardly and forwardly over said flue outlet, the space between said member and said outlet being free and unobstructed at the front and both sides, said member having louvers, and incombustible impurity collecting material disposed at the back of said member.
10. A device for the purpose described comprising substantially concentric inner and outer spaced connected members providing a passage open at its ends, incombustible impurity collecting means interposed in said passage between said members, said inner member having louvers communicating with said passage, and means for connecting said device to a gas stove so that the said device projects upwardly and forwardly over the flue outlet, the space between said device and said flue outlet being free and unobstructed at the front and both sides.
- In testimony whereof I affix my signature.
- PAUL J. HENTSCHEL.
